BED AND THE LIKE

Filed July 9, 1934

Inventor:

Thomas M. Butler,
By Joshua R. Hogue
his Attorney.

UNITED STATES PATENT OFFICE

2,036,395

BED AND THE LIKE

Thomas M. Butler, Chicago, Ill.

Application July 9, 1934, Serial No. 734,300

4 Claims. (Cl. 5—329)

This invention relates to improvements in beds and has for an object the provision of means for dividing a bed into two portions, separating one portion from another. As is well known, 5 many sleepers are restless and cause annoyance to others resulting in loss of sleep and consequent injurious effects. To overcome these objections I have devised means in the form of a board partition running lengthwise of a bed for 10 the purpose of dividing the bed into separate portions.

A particular object of the invention is the provision of a device which will not mutilate or mar the frame of a bed to which it is to be 15 applied and which may be readily attached or detached as a unit.

Other objects will appear hereinafter.

The invention consists in the combinations and arrangements of parts hereinafter described 20 and claimed.

The invention will be best understood by reference to the accompanying drawing forming a part of this specification, and in which:

Fig. 1 is a longitudinal elevational view, partly 25 in section, taken from the side of a bed, showing an adaptation of the device;

Fig. 2 is a plan view of the partition element and the connecting members;

Fig. 3 is a view similar to Fig. 1 but showing 30 the device applied to a wooden frame of a bed;

Fig. 4 is an enlarged vertical sectional view of the foot end of a bed shown in Fig. 1; and,

Fig. 5 is a detail view of the attaching and 35 securing member.

Referring to the form shown in Fig. 1, the device is applied to a metal bed having a tubular foot end support 10 and a tubular head end support 11. The foot end support 10 has an upper tubular cross member 12 and the lower portion 40 has a corresponding tubular cross member 13. The head end support 11 is similarly provided with an upper tubular cross member 14 and a lower tubular cross member 15. The end supports 10 and 11 are linked together by means 45 of a pair of tie rods 16, one of which is shown in Fig. 1. The tie rods support the usual spring 17, mattress 18, and covering 19.

For the purpose of rendering the device of the present invention readily applicable for the purpose mentioned, there is provided an attaching member 20 having at its upper extremity an engaging ring 21 to which is secured one end of a tension spring 22, the opposite end of which is secured to an intermediate ring 23. The purpose 50 of the intermediate ring 23 is to facilitate ap-

plication of the device by inserting the finger and pulling downwardly to engage the bottom ring. The upper portion of the tension spring 22 is preferably covered with a protective member 24 of rubber or similar material to prevent 5 marring of the bed frame, and for a similar purpose there is provided adjacent the lower end of tension spring 22 a rubber shoe 25. Connected to the intermediate ring 23 is a cord 26 which is secured to a lower attaching ring 27. 10

The partition 28 preferably comprises a rectangular board 29 composed of wood or other material, the length of which is preferably shorter than the normal distance between the head end and foot end of a bed. In order to 15 enable the partition to be connected in use to the attaching device described, there are provided a plurality of eye-bolts 30 having eyes 31 at each end of the partition. These eye-bolts are threaded and are adapted to engage in 20 a countersunk plate 32 secured to the ends of the partition by screws 33, the threaded shanks of the eye-bolts having engagement with the threaded portion 34 in the respective plates. In order to permit of the eye-bolts being extended 25 and withdrawn relative to the partition, the partition adjacent each eye-bolt has a bore 35 for the reception of the bolt shank.

In operation and use the partition 23 rests 30 endwise upon the covering 19 so as to divide the surface of the bed into two portions. By the arrangement disclosed the eyes of each pair of eye-bolts may be arranged to align vertically with the upper ring 21, and to complete the attachment a locking rod 36 is inserted downwardly through ring 21 of the attaching member 20, thence through eyes 31 of the eye-bolts for lower engagement by ring 27. The locking rods 36 are maintained in this position by reason of contact against the upper rings 21 of the enlarged heads 37 of the rods. The upper portion of each rod 36 is preferably covered with a resilient material such as rubber or the like, to prevent marring, similar to the provision made with respect to the upper portion of the attaching member 20. In Fig. 3 there is illustrated a manner of attaching the device to a wooden bed frame having a foot end 39. 40 45

It will be manifest from the foregoing that I have provided partitioning means and effective 50 means for locking said means in position and means for adjusting the partitioning means to fit beds of different sizes. If it is desired to use a partition of a particular size with a larger bed all that is necessary is to manipulate the eye-bolts 55

in the nuts outwardly from the cleats and partition and vice versa.

While I have shown concrete exemplifications of the application of the principle of my invention these forms do not circumscribe my invention but my invention is capable of being exemplified in a large variety of forms.

It will be apparent that by my invention means easy of handling have been provided to accomplish the objects set forth. In addition, by the means I have provided as will be apparent it will be a simple matter to remove the covering and the like. It will also be apparent that my invention is capable of application to any bed and that the means provided are not only simple in operation and manufacture, but are inexpensive, besides being capable of ready application by any one.

While I have illustrated and described the preferred form of construction for carrying my invention into effect this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a device of the kind described a bed frame having a foot end support and head end support and tie rod means connecting said supports, a partition for dividing said bed into two portions, eye-bolts secured to the respective ends of said partition, locking rod means adapted to be inserted through said eye-bolts, and an attaching member provided with tension means for en-

gaging a locking rod at opposite ends and extending over an end support.

2. In a device of the kind described a bed frame having a foot end support and head end support and tie rod means connecting said supports, a partition for dividing said bed into two portions, eye-bolts secured to the respective ends of said partition, locking rod means adapted to be inserted through said eye-bolts, and an attaching member having a tension spring and provided with rings for engaging a locking rod at opposite ends for maintaining said partition in position adjacent an end support.

3. In a device of the kind described a bed frame having a foot end support and head end support and tie rod means connecting said supports, a partition for dividing said bed into two portions, eye-bolts secured to the respective ends of said partition, locking rod means adapted to be inserted through said eye-bolts, and an attaching member having a tension spring with rings for engaging a locking rod at opposite ends and provided with an intermediate ring for manual engagement.

4. In a device of the kind described a bed frame having a foot end support and head end support and tie rod means connecting said supports, a partition for dividing said bed into two portions, eye-bolts secured to the respective ends of said partition, locking rod means adapted to be inserted through said eye-bolts, and an attaching member having a tension spring and provided with rings for engaging a locking rod at opposite ends for maintaining said partition in position adjacent an end support, said locking rod having an upper enlarged head adapted to rest upon the upper ring of said attaching member.

THOMAS M. BUTLER.
